UNITED STATES PATENT OFFICE.

PAUL SZATHMÁRY, OF CLARENCE, NEW YORK.

DESIGN FOR A CENTERPIECE FOR TABLES.

42,115.

Specification for Design.

Patented Jan. 23, 1912.

Application filed October 30, 1911. Serial No. 657,618. Term of patent 3½ years.

To all whom it may concern:

Be it known that I, PAUL SZATHMÁRY, a subject of the King of Hungary, residing at Clarence, in the county of Erie and State of New York, have invented a certain new, original, and ornamental Design for Centerpieces for Tables, of which the following is the specification, reference being had to the drawing forming a part thereof.

The figure is a perspective view of the centerpiece for tables, illustrating my new design.

I claim:

The ornamental design for a centerpiece for tables, as shown.

PAUL SZATHMÁRY.

Witnesses:

SIPOS JOSEF,

LOIS IGNATZ.
